Application filed December 7, 1921. Serial No. 520,753. Term of patent 14 years.

To all whom it may concern:

Be it known that I, BENJAMIN GOTTLIEB, a citizen of the United States, residing in the city of New York, borough of Brooklyn, in the county of Kings and State of New York, have invented a new, original, and ornamental Design for Tire Treads, of which the following is a specification, reference being had to the accompanying drawing, forming part thereof.

My design consists essentially of a series of rows of approximately elliptical shaped raised figures, each row of said raised figures joined to the next adjacent row by obliquely extending ribs.

I claim:
